UNITED STATES PATENT OFFICE.

ALMARON J. SCOFIELD, OF BELOIT, WISCONSIN, ASSIGNOR TO WILLIAM A. KNAPP, OF SAME PLACE.

COMPOUND FOR PREVENTING BOILER INCRUSTATION.

SPECIFICATION forming part of Letters Patent No. 897,523, dated February 12, 1889.

Application filed June 30, 1888. Serial No. 278,701. (No specimens.)

To all whom it may concern:

Be it known that I, ALMARON J. SCOFIELD, of Beloit, in the county of Rock and State of Wisconsin, have invented certain new and useful Improvements in Compounds for Clarifying Water; and I do hereby declare the following to be a full, clear, and exact description of the invention, such as will enable others skilled in the art to which it appertains to make and use the same.

My invention relates to an improvement in compositions of matter for clarifying water, and more particularly for preventing and removing incrustation from boilers, and has for its object to provide a compound for removing and preventing incrustation in boilers and clarifying water generally.

With this object in view my invention consists in certain novel combinations of ingredients, as hereinafter set forth.

The compound which I employ for the prevention and removal of incrustation is composed of barley-sprouts, (from malt,) one part, flaxseed or flaxseed - meal or flaxseed 25 pounds, one part; glue, one part, pulverized and mixed as a powder, and a sufficient amount of water to dissolve the glue if the compound should be desired in blocks or forms. These ingredients are thoroughly 30 mixed together, and the use of the resulting compound produces very satisfactory results

for the clarification of water and the removal and prevention of incrustation from boilers.

Very good results may be obtained from a mixture of flaxseed and glue, barley-sprouts 35 and glue, flaxseed and barley-sprouts, or flaxseed mixed with water.

It is evident that the proportions of ingredients might be varied without departing from the spirit of my invention or limiting its 40 scope, and hence I do not wish to limit myself to the precise proportions herein stated, but prefer to use one-third of each or one-half of each when either of the three is not used.

Having fully described my invention, what I 45 claim as new, and desire to secure by Letters Patent, is—

1. A compound for clarifying water, composed of flaxseed or flaxseed compounds and glue, substantially as set forth. 50

2. A compound for preventing and removing incrustation in steam-boilers, composed of flaxseed or flaxseed compounds, glue, and barley-sprouts, in substantially the proportions stated. 55

In testimony whereof I have signed this specification in the presence of two subscribing witnesses.

ALMARON J. SCOFIELD.
